UNITED STATES PATENT OFFICE.

HENRY BRANCHLER, OF GREENSBURG, PENNSYLVANIA, ASSIGNOR OF ONE-HALF TO JAMES WIMER, OF SAME PLACE.

BLACKSMITH'S HEARTH.

SPECIFICATION forming part of Letters Patent No 337,735, dated March 9, 1886.

Application filed October 12, 1885. Serial No. 179,593. (No model.)

To all whom it may concern:

Be it known that I, HENRY BRANCHLER, a citizen of the United States, and a resident of Greensburg, in the county of Westmoreland and State of Pennsylvania, have invented certain new and useful Improvements in Blacksmiths' Hearths; and I do hereby declare that the following is a full, clear, and exact description of the invention, which will enable others skilled in the art to which it appertains to make and use the same, reference being had to the accompanying drawings, which form a part of this specification, and in which—

Figure 1 is a vertical sectional view of my improved blacksmith's hearth. Fig. 2 is a similar view of the same, taken at a right angle to Fig. 1. Fig. 3 is a side view of the tuyere, showing parts of the hearth broken away; and Fig. 4 is a horizontal sectional view on line *xx*, Fig. 3.

Similar letters of reference indicate corresponding parts in all the figures.

My invention has relation to blacksmiths' hearths, and more especially to the tuyere part of such hearths; and it consists in the improved construction and combination of parts of the same, as hereinafter more fully described and claimed.

In the accompanying drawings, the letter A indicates the brick-support for the hearth, and B indicates the bowl, in which the fire is kept, and which has the aperture C in its middle. The bowl has a neck, D, formed around the aperture, which neck fits into a vertical chamber, E, which is provided at its lower end with a slide, F, and which has the blast-pipe G entering its side near its upper end. Two rock-shafts, H H, are journaled in the upper end of this chamber immediately below the neck 40 of the bowl, and have two wings, I I, projecting into the chamber and nearly closing its upper end when placed horizontal, the rock-shafts bearing against the walls of the chamber. The rock-shafts are provided at one end 45 with cogged segments J, meshing with each other, and one shaft is extended and provided with a suitable handle or lever, K, for rock-ing it.

It will now be seen that as the rock-shafts 50 are turned to bring the wings to point down-

ward the aperture between them will be increased, allowing a greater quantity of blast to pass up through the fire, and when the wings have been turned sufficiently down, so as to occupy a vertical position, or nearly so, the 55 cinders from the fire may fall down into the chamber, and be emptied out by drawing the slide out at the bottom of the chamber, so that the fire may be renewed or the cinders emptied out without disturbing the irons which rest 60 in the fire.

The slide in the bottom of the chamber will prevent the blast from escaping through the aperture in the bottom of the chamber, and the chamber will serve to equalize the blast as 65 it enters the chamber and fills the same before ascending through the aperture at the top of the chamber, so that if there is any inequality in the blast it will not be felt in the fire, the chamber serving as a store-room for the blast, 70 from which it may pass into the fire.

The blast may be regulated by opening or closing the wings or gates upon the rock-shafts, while still keeping their inner edges sufficiently close together to prevent the cinders from falling through the aperture between them, and when the fire gets dull from accumulation of cinders they may be dumped down into the chamber by opening the gates under the aperture of the bowl, when the cinders, which will 80 be immediately above and upon the aperture in the bowl, will drop through the aperture, while the live coal and the coal which has not yet been consumed will remain in the bowl, and may be raked toward the middle of the same. 85 In this manner the fire may be kept up continually without any necessity for raking the fire off from the hearth for the purpose of cleaning the aperture in the bowl, and the fire may be relieved from cinders without even removing 90 the irons from the fire.

It follows that this hearth or tuyere may be used in a stationary hearth as is generally found in a blacksmith's shop, or it may be adapted to fit into the several forms of portable hearths, my improvements being independent of the means for creating the blast, as well as of the shape of the bowl and its support, being adaptable to any construction of bowl and support.

I am aware that it is not new to provide a blacksmith's tuyere with pivoted gates or doors by means of which the draft can be regulated, and I do not claim such construction, broadly; but

I claim and desire to secure by Letters Patent of the United States—

1. In a blacksmith's tuyere, the combination, with the bowl having the aperture in its middle, of two downwardly opening gates having cogged segments upon their pivotal shafts meshing with each other, said gates being so arranged that their edges always approach each other directly underneath the middle of the aperture in the bowl, as and for the purpose shown and set forth.

2. In a blacksmith's tuyere, the combination of a bowl having an aperture at its middle surrounded upon its underside with a neck or flange, a downwardly-extending chamber

having its upper end fitting upon the neck, and having the blast-pipe entering its side near the upper end, and having an aperture at its lower end, two rock-shafts journaled in the upper end of the chamber, bearing against the sides of the chamber, and having wings upon their inner portions for closing the chamber, and having cogged segments upon their shafts meshing with each other, and means for rocking them, and a slide covering the aperture in the bottom of the chamber, as and for the purpose shown and set forth.

In testimony that I claim the foregoing as my own I have hereunto affixed my signature in presence of two witnesses.

HENRY BRANCHLER.
